CLAIM

The ornamental design for an oil flow rack, as shown and described.

DESCRIPTION

FIG. 1 is a front perspective view of an oil flow rack according to my new design;

FIG. 2 is a front elevational view thereof;

FIG. 3 is a right side elevational view thereof, the left side being a mirror image of the right side;

FIG. 4 is a rear elevational view thereof; and,

FIG. 5 is a top plan view thereof.
